UNITED STATES PATENT OFFICE.

GEORGE W. CLARKE, OF SANTA MONICA, CALIFORNIA, ASSIGNOR, BY DIRECT AND MESNE ASSIGNMENTS, OF ONE-HALF TO FRANCIS M. WRIGHT, OF SAN FRANCISCO, CALIFORNIA.

PRINTER'S STICK.

1,093,111.

Specification of Letters Patent. Patented Apr. 14, 1914.

Original application filed November 27, 1903; Serial No. 182,936. Divided and this application filed March 26, 1910, Serial No. 551,698. Renewed September 9, 1913. Serial No. 788,933.

To all whom it may concern:

Be it known that I, GEORGE W. CLARKE, a citizen of the United States, residing at Santa Monica, in the county of Los Angeles and State of California, have invented new and useful Improvements in Printers' Sticks, of which the following is a specification.

This invention relates to an improved form of printer's stick, intended to be employed with the matrix plates invented by me and forming the subject of a separate application filed November 27, 1903, of which this is a division, a patent being granted on said application, July 26, 1910, No. 965,155.

In the accompanying drawing, Figure 1 is an end view of the printer's stick used in my apparatus, showing the same in the position before use; Fig. 2 is a perspective view showing said stick in use and ready for casting; Fig. 3 is a perspective view of a strip of paper or cardboard used for making a combination metal and cardboard slug; Fig. 4 is a transverse section of the mold showing the slug cast therein; Fig. 5 is a perspective view of the combination metal, and paper slug; Fig. 6 is a perspective view of the removable adjustment block; Fig. 7 is a perspective view of a pair of spacing wedges; Fig. 8 is a perspective view of a series of such matrix plates set up to cast a line of type for a single word.

My stick is in the form of a box open at the top, having one side, 1, movable slightly outward, guided by screws 2 in holes in the upper bar of the side 1. Both the movable side 1 and the fixed side 3 have longitudinal slots 4, to receive the lower parts of spacing wedges 5, 6. These wedges are formed in pairs, a short wedge 5 and a long one 6. Each wedge has a longitudinal slot 7 in the middle, and through said slots 7 pass the two upper bars 8 which form the upper portions of the sides of the stick. The wedges are thus movable longitudinally on the stick, but do not drop therefrom when the stick is inverted to dump the matrix plates after casting. The sides 1 and 3 are cut through at one end, as shown at 9, to allow the lower parts of the wedges to be passed into the slots 4, before the sides 1 and 3 are attached to the end pieces 23. When said lower parts only of the wedges have been passed into the

slots 4, the slots 7 of the wedges are passed over the upper corner of the sides 1 and 3 above said slots to the position shown in Fig. 2. These wedges are stored in the apparatus permanently at one end thereof, ready as occasion requires to be used for separating matrix plates to form words in the composition of a line. The short wedges 5 have their slots about the same length as the width of the stick, so that they cannot be moved across the stick, but the long wedges 6 are intended to be moved across the stick, the effect of such movement being to increase or decrease, according to the direction of the movement, the combined thicknesses of the two wedges. The matrix plates used with this invention are fully described in said patent above referred to. Each is square in form and is formed with 8 matrices, two on each edge of said plate, each adjacent to one corner thereof. There are also stamped or otherwise formed on the sides eight index characters which correspond to the several matrices, each index so formed having the same location on the plate relative to its matrix therein. The matrix plates are placed in the stick so that the matrices corresponding to the several letters cast are in a straight line, as shown at 22, in Fig. 8.

After the operator has placed in the stick 85 the matrix plates 10 for the first word of the line, he moves up next to said matrix plates, from the right hand end of the stick, a pair of spacing wedges; he then places in the stick the matrix plates of the next 90 word, and moves up another pair of spacing wedges; and so on until the line will hold no more. The length of the working portion of the box is regulated for a given length of line by means of a U-shaped block 95 11 of corresponding length, selected from a number of such blocks of varying lengths. Having now prepared a line of matrices proper for casting a type line, the line of type may be formed from this line of matrices in many ways.

The mold may be a separate device from the printer's stick, or may be attached to it, as desired. I herein illustrate an advantageous arrangement of the latter character. 105 On the rear side of the stick, is pivoted, as shown at 12, a mold section 13. To this is again pivoted a second section 14. These

sections have an inlet 15 and a vent hole where necessary. These mold sections are arranged to be swung over on to the top of the matrix plates to form a mold over the 5 matrices. After the line is filled, the operator brings the edges of the matrices to an even surface, the side edges by pressing in the movable side 1, and the top edges by pressing down the mold sections. This he 10 can easily do, because the matrix plates do not generally fill up the box tightly, even when it can hold no more. Holding the movable side and mold sections against the matrices to keep the surfaces even, he now 15 pushes all the long wedges transversely across the stick; this may be conveniently done by pressing the ends of said long wedges all together against a level surface, as that of the table. This tightens up and 20 binds all the matrix plates, and at the same time automatically spaces the words at uniform distances. The thick end of the long wedges are preferably arranged at the same side of the box as its loose side, so that the 25 pressure in pushing up the long wedges tends to close said loose side. The mold is clamped down upon the matrices by the eccentrics 16 which are operated by a cross-bar 17 and pivoted upon the end pieces 23, 30 said eccentrics engaging downwardly extending arms 18 from the mold section 14, and then the mold is ready for the injection of the molten type metal. After casting, the eccentrics are removed, the mold sec- 35 tions thrown back and opened, discharging the line of type, the spacing wedges pressed back to their original position, releasing the matrix plates, and the latter are then dumped out ready for use for another type 40 line.

The apparatus illustrated in Figs. 3, 4, 5, shows a mold for casting a combination paper and metal slug. The mold cavity is made, for the greater part of its depth, 45 only wide enough to receive a strip of paper or cardboard, shown at 20. This strip has a line of perforations 21 at its edge which is placed next the matrix plates, to allow the molten type metal to flow through and 50 join the type face to the strip. The strip is placed between the two mold sections which are then pressed together and laid on the matrix plates, and the casting is then made.

55 The combination paper and metal slug especially is useful in work where wide spacing between lines is required. With the construction there is a saving of 75 per cent. in type metal over the solid slug and 60 a saving of labor in handling by reason of lightness in weight.

I claim:—

1. In combination with a series of plates having thereon type-forming devices, a 65 printer's stick for said plates, having a bot-

tom adapted to support the plates, slotted sides adapted to confine the vertical edges of the plates, ends adapted to confine lengthwise a series of such plates, and an open top through which the plates can be inserted in the stick, and spacing devices for the plates, having parts movable through said slots at right angles to said sides and in a direction parallel with the plane of said bottom, substantially as described. 75

2. In combination with a series of plates having thereon type-forming devices, a printer's stick for said plates having a bottom adapted to support the plates, slotted sides adapted to confine the vertical edges of the plate, ends adapted to confine lengthwise a series of such plates, and an open top through which the plates can be inserted in the stick, and spacing devices, having parts adapted to move transversely through said slots and having recesses adapted to receive parts of said sides adjacent to the slots, substantially as described. 80

3. In combination with a series of plates having thereon type-forming devices, a printer's stick for said plates consisting of a bottom to support the plates, side supports for said plates, and ends for confining lengthwise a series of plates, the stick being open at the top for the insertion of the plates therein, and spacing devices slideable on said side supports in a direction parallel to the plane of the bottom, substantially as described. 100

4. In combination with a series of plates having thereon type-forming devices, a printer's stick for said plates consisting of a bottom to support the plates, side supports for said plates, and ends for confining lengthwise a series of plates, the stick being open at the top for the insertion of the plates therein, and spacing devices slideable both transversely and longitudinally on said side supports in a direction parallel to the plane of the bottom, substantially as described. 105

5. In combination with a series of plates having thereon type-forming devices, a printer's stick for said plates, consisting of a bottom upon which the plates can rest, sides arranged to contact with the vertical edges of the plates, and ends for confining lengthwise a series of such plates, and spacing devices secured to the sides of said stick but movable longitudinally and transversely relative thereto, substantially as described. 110

6. In combination with a series of plates having thereon type-forming devices, a printer's stick for said plates, pairs of spacing wedges, each pair comprising a long wedge and a short wedge, said wedges tapering in opposite directions, the short wedges being substantially immovable transversely of the stick, and the long 115

wedges being movable transversely thereof, the side of the stick being slotted and said wedges being also slotted and co-engaging with the slotted sides of the stick to retain the wedges thereon, substantially as described.

7. A printer's stick adapted to contain a series of matrix plates and having a fixed side and a loose side, and pairs of spacing wedges, each pair comprising a short wedge

and a long wedge, the thick ends of the long wedges being at the same side of the box as its loose side, substantially as described.

In testimony whereof I have hereunto set my hand in the presence of two subscribing 15 witnesses.

GEORGE W. CLARKE.
